UNITED STATES PATENT OFFICE.

WALTER S. RUSH, OF NEW YORK, N. Y.

ELECTRIC SIGNAL APPARATUS FOR MARINE ORDER-TRANSMITTING MECHANISM.

1,259,296.

Specification of Letters Patent. Patented Mar. 12, 1918.

Application filed March 15, 1913. Serial No. 754,641.

To all whom it may concern:

Be it known that I, WALTER S. RUSH, a citizen of the United States, residing at New York city, in the county and State of New York, have invented certain new and useful Improvements in Electric Signal Apparatus for Marine Order-Transmitting Mechanism, of which the following is a specification.

10 My invention relates to ships' order-transmitting mechanism and has for its object to provide electrical means to indicate either that the signals transmitted have been correctly received, that the signal-transmitting apparatus is not in working order, or both of these conditions; and which may be utilized, in case the signal-transmitting mechanism is out of order, as an auxiliary signal-transmitting system.

20 In the accompanying drawings—

Figure 1 is a diagrammatic plan view illustrating my invention embodied in a ship's order-transmitting mechanism of the ship's telegraph type;

25 Fig. 2 is a diagrammatic view illustrating the invention applied to an order-transmitting device of the bell-pull type; and

30 Fig. 3 is another diagrammatic view illustrating a further adaptation of the invention to the bell-pull type of apparatus.

As is well known, a ship's order-transmitting apparatus comprises an instrument or device located in the pilot house, or at any other convenient position, arranged to be operated by the pilot or master of the vessel, and which, as a whole, I herein term the order-transmitting device,—another device located in the engine room for receiving the orders and communicating them to the engineer,—and which, as a whole, I herein term the order-receiving device,—and connecting means between these two devices whereby the movements imparted to the former are communicated to the latter. For well-known

45 reasons it has been found that the best results are attained when these connecting means are positive and mechanical in their nature, and it is in connection with transmitting and receiving devices thus connected

50 that my invention is employed.

Referring to Fig. 1, 2 designates an order-transmitting device of common type, and 3, the order-receiving device, these two being connected by wires, cables, or equivalent positive, mechanical connections, designated

55 4. 5 indicates the gong located in the engine

room adjacent to the order-receiving device. This is arranged to be struck by the pivoted hammer 6 which is acted upon by the spring 7. The connecting wires or cables 4 are arranged to turn a shaft 9, on which are mounted the indicating hand 8 of the order-receiving device and a toothed wheel 10. The teeth of this wheel operate upon a vibrating lever 11 that in turn acts upon the stem 12 of the bell hammer 6. The lever is formed with two arms 13, 14, which extend in opposite directions from the fulcrum of the lever, and are of different lengths so as to impart the requisite movements to the bell hammer, in whichever direction the lever may be turned, and accordingly as the toothed wheel 10 is rotated.

15 indicates an electric circuit in which is located a battery 16, or other source of electric current, and indicating devices 17. These latter may be of any desired kind, either visual or audible, and one at least of them is located in proximity to the order-transmitting device 2, and another adjacent to the receiving device 3. The circuit is normally open at the point 18; but is arranged to be closed by a bridge piece 19 carried by the stem of the bell hammer whenever the latter is moved back by the lever 11 preparatory to striking a blow upon the bell or gong 5.

In the arrangement shown in Fig. 1 a movement of the handle of the order-transmitting device from one point to the next 90 operates to move the toothed wheel 10 at the order-receiving device an extent equal to the distance between two adjacent teeth, with the result that one of them is carried past, and therefore operates, the lever 11, 95 and, through it, the bell hammer, which thereupon strikes one stroke upon the gong, the spring 7 insuring this, the moment a tooth of the wheel 10 passes the end of the lever. As the hammer is being drawn back 100 against the tension of the spring 7 preparatory to striking its blow, the bridging piece 19 closes the electric circuit at 18, whereupon there is a momentary signal given at each of the indicating devices 17 located in the circuit 15. If the order desired to be transmitted is correctly delivered this closing of the circuit with the incident operation of the signals 17 is but momentary and shows that the signal has been correctly received. If for any reason the movement of the handle of the order-transmitting instru-

ment fails to produce a like movement at the receiving instrument, as might occur due to excessive slackness in the connections 4, one of two conditions would result: First, the movement imparted to the wheel 10, and through it and the lever 11 to the bell hammer, might not be sufficient even to close the electric circuit at 18, whereupon there would be no operation of the signals 17, and the pilot would instantly know that his order had not been properly transmitted, and thereupon he should move the handle of his instrument farther, and until the correct response upon the electric signal 17 was received; or, second, the movement imparted to the bell hammer might be greater than that last supposed and sufficient to close the electric circuit at 18 but not enough to release the lever 11 from the tooth of the wheel 10, which would result in holding the circuit closed at 18, whereupon the signals, given by devices 17, would continue until the handle of the transmitting device had been moved sufficiently far to cause the wheel 10 to clear the lever and release the bell hammer, which amount of movement would place the hand 8 of the receiving instrument in position to unmistakably indicate the order intended to be transmitted.

Should one or both of the wires or cables 4 be broken there would then of course be no response at the device 3 to the movements given at the device 2, and this would be indicated by failure of the electrical apparatus to give any signal or indication whatever.

It will thus be seen by the mechanism described that the pilot under all conditions—day or night—is instantly advised, first, whether or not the apparatus is in proper working condition, and, second, if it is, that the order he intended to transmit has been properly received.

In Fig. 2 there is shown an adaptation of my invention to a ship's order-transmitting mechanism of the ordinary bell-pull type. Referring to this view, 20 indicates the bell-pull handle by which the pilot transmits the order, it being connected by wires or cables 4 with the stem of a bell hammer 6 arranged to strike the gong or bell 5. A spring 7 acts upon the stem of the bell hammer, and another spring 21 is arranged to act upon the stem of the pull handle 20.

The electric circuit 15, including the battery 16, and various signal-giving devices 17, is like the electric circuit already described in connection with Fig. 1, being open at 28 adjacent to the receiving instrument, which in this case is the gong 5. The circuit is adapted to be closed at the point 28 by the bridge piece 29 carried by the stem of the bell hammer whenever the latter is in normal position of rest and in position to strike a blow upon the bell. The cir-

cuit is also broken at the point 22 adjacent to the order-transmitting device and is here arranged to be closed by a bridge piece 23 carried by the stem 24 of the pull handle 20 when that is moved to the proper extent to operate the signal-receiving device.

The arrangement shown in Fig. 2 is adapted to notify the pilot or master when his orders are not being delivered by reason of the breakage or other failure on the part of the mechanical connection 4 to transmit movements from the order-sending to the order-receiving device. When the apparatus is operating properly the circuit is broken at 28 and is closed at 22 each time an order is transmitted, but as the break at 28 takes place before the closing of the circuit at 22, no signals are given at the devices 17, for the circuit is, at one or the other point, always open. Should, however, the wire or cable 4 be broken, a pull upon the handle 20 will not move the stem of the bell hammer, and consequently the circuit will remain closed at 28 and will be completed at 22, so that the electric signals will be given, indicating that the mechanical apparatus is out of order and the mechanically transmitted orders not being properly received.

In Fig. 3 an order-transmitting device of the bell-pull type is shown equipped with electrical signal-giving apparatus similar to that just described, and shown in Fig. 2, and also equipped so as to show that the signals intended to be transmitted are being properly received. For this latter purpose there is an electric circuit 25 connected with the battery 16 in parallel with the circuit 15, and including signal devices 27 of suitable kind. This latter circuit is open at 38 and is arranged to be closed by a bridge piece or circuit-closer 39 carried by the stem of the bell hammer 6 whenever the latter is drawn back preparatory to delivering its blow upon the gong 5.

I arrange an easily operated, manually-controlled circuit-closer 30, adjacent to the signal-sending device. It is arranged so that the pilot can close the circuit 15 and thus transmit electrical signals through said circuit to the engineer independently of the mechanical signal-sending devices. By this arrangement whenever the mechanical apparatus is not in working condition this electrical transmitting means may be resorted to. It also furnishes an easy and reliable method of testing the devices and may be employed to familiarize both the pilot and the engineer with the use of electric signals.

It will be seen from the description of these several embodiments of my invention that the mechanical connecting means between the order-transmitting and the order-receiving devices is made to control the

opening and closing of an electric circuit in which are placed indicating signals by which the working of the system, or its failure to work, is indicated; and that, as is preferred, and as is shown in the drawings, a part of the order-receiving instrument is utilized as part of the circuit-controlling devices. The representation of several signaling devices, 17 and 27, in each circuit is for the purpose of indicating that these devices may be located in different parts of the vessel and arranged to operate simultaneously, if desired, so that the signals may be duplicated in various parts of the ship or at such points as may be desired.

What I claim is:—

1. In a ship's signal apparatus, the combination of a signal-sending device, a signal-receiving device, including a gong and a striking hammer therefor, mechanical connections between these two devices, an electric circuit including a signal-giving device, the circuit being broken adjacent to the hammer of the gong, means located adjacent to the signal-sending device by which the circuit may be opened and closed at will, and a circuit-closing device carried by the striking hammer of the gong arranged to automatically open and close the circuit as the said hammer is operated.
2. In a ship's signal apparatus, the combination of a signal-sending device, a signal-receiving device, including a gong and a striking hammer therefor, mechanical connections between these two devices, an electric circuit including a signal-giving device

and being broken at two points, circuit-controlling means operated by the signal-sending device for controlling one break in the circuit whenever a signal is sent, and other means operated by the hammer of the gong for controlling the other break in the circuit whenever the said hammer is operated.

3. In a ship's signal apparatus, the combination of a signal-sending device, a signal-receiving device, mechanical connections between these two, an electric circuit including a signal-giving device, the circuit being broken at two points, and circuit closers at the said points, the said circuit closers being arranged to be alternately operated when the system is in working condition by the said mechanical connections.

4. In a ship's signal apparatus, the combination of a signal-sending device, a signal-receiving device, mechanical connections between these two, an electric circuit including a signal-giving device, the said circuit being open at two points respectively near the sending and the receiving devices, and circuit closers located at the said points and arranged to be operated alternately through the said mechanical connections when the system is in working condition, the circuit at the break near the receiving device being normally closed and that at the sending device normally open.
